C. E. ANDREWS.

PHTHALIC ANHYDRID,

APPLICATION FILED OCT. 14, 1919.

1,336,182.

Patented Apr. 6, 1920.

by Chester E. Andrews
Attorney.

UNITED STATES PATENT OFFICE.

HESTER E. ANDREWS, OF PITTSBURGH, PENNSYLVANIA, ASSIGNOR TO THE SELDEN COMPANY, OF PITTSBURGH, PENNSYLVANIA, A CORPORATION OF PENNSYLVANIA.

PHTHALIC ANHYDRID.

1,336,182.

Specification of Letters Patent.

Patented Apr. 6, 1920.

Application filed October 14, 1919. Serial No. 330,560.

To all whom it may concern:

Be it known that I, CHESTER E. ANDREWS, a citizen of the United States, residing at Pittsburgh, in the county of Allegheny and 5 State of Pennsylvania, have invented certain new and useful Improvements in Phthalic Anhydrids, of which the following is a specification.

The present invention has for its object a 10 commercial article of manufacture, phthalic anhydrid, which is substantially chemically pure. Phthalic anhydrid of this kind may be manufactured in accordance with processes hereinafter described. One such 15 process consists of forcing a mixture of naphthalene vapor and air at a temperature of about 350° to 550° C., (preferably about 450° C.) over or through a suitable catalyst such as molybdenum oxid. There is thereby 20 produced a mixture consisting essentially of phthalic anhydrid and other oxidation products of naphthalene, such as phthalic acid, 1-4-naphthoquinone, benzoic acid, some water, and some unchanged naphthalene, which 25 mixture may be then led to a condenser and condensed or fractionally condensed, and the resultant products suitably separated. The reaction product may then be treated in an apparatus as hereinafter described.

30 In the accompanying drawings, the figure is a vertical sectional view through one type of apparatus that may be employed.

In said apparatus the said reaction product as produced by the before mentioned 35 oxidation process is introduced into a closed container 1 by means of a filling funnel 2, or through any other suitable instrumentality, and is heated by any suitable means, as for instance, burners 3. A blast of gas suitable 40 for use as a vehicle is passed over the material, preferably being introduced by a centrifugal fan 4 having a discharge nozzle 5 entering one end of the container 1. Baffle plates 6 may be located within the container. The vapor-laden gases are conducted 45 by a conduit 7 into a suitable condenser. Thus, in the disclosure illustrated, a casing 8 is employed having portions or sections of successively increasing height, designated 9, the conduit 7, discharging into the smallest 50 chamber. These chambers or compartments are defined by suitable screens 10 through which the vapors pass, and separate draw-off doorways 11 are provided in the different compartments. Means are provided for

governing the temperatures of the different compartments, said means being in the form of spray nozzles 12 supplied through branch pipes 13 from a main 14. The residue gas, after passing through the condenser, may be 60 returned through a conduit 15 to the fan 4, and provision is made for heating the same, as for example, burners 16.

As an example, phthalic anhydrid, having a melting point of approximately 128 degrees, centigrade, and a boiling point of 284 degrees, centigrade, with which is mixed naphthalene having a melting point of 80 degrees, centigrade, and a boiling point of 218 degrees, centigrade, together with other 65 oxidation products of naphthalene, is placed in the container 1, and is subjected to a temperature of between 150 degrees, centigrade, and 200 degrees, centigrade, the container and the gas being properly heated by the 70 burners 3 and 6 respectively. The gas is one that will be inert at the temperature employed. The vapor laden gas, passing through the conduit 7, is delivered into the condenser, wherein a fractional condensation is effected, resulting in the crystals constituting the invention, being deposited in the first two or three compartments and on the screens defining the same when said compartments are maintained at a temperature 75 of between about 70 degrees, centigrade, and about 115 degrees, centigrade. Those crystals which are deposited on the screens are 80 dislodged by suitable weights, as 17, which can be swung against the screens periodically to dislodge the product therefrom.

The phthalic anhydrid produced according to this invention consists of colorless needle-like crystals, is substantially chemically pure, being free from benzoic acid, 95 sulfur, chlorin, mercury, water, and only slight traces of phthalic acid and has a melting point above 130 degrees, centigrade, (corrected).

These characteristics establish this 100 phthalic anhydrid as a new commercial product as shown by its high melting point. As a consequence, many advantages result from its use in the industries. For example, less trouble is experienced in the purification 105 of phenolphthalein made therefrom. Certain dyes are obtained in more brilliant shades when this product is used, as for example, various members of the rhodamin group.

Having thus fully described my invention, what I claim as new, and desire to secure by Letters Patent, is:—

1. As an article of manufacture, phthalic anhydrid being substantially chemically pure and having a melting point above 130 degrees, centigrade, (corrected).
- 5 2. As an article of manufacture, phthalic anhydrid in the form of colorless needle-like

crystals substantially chemically pure and 10 having a melting point above 130°, centigrade, (corrected).

In testimony whereof I affix my signature in the presence of two witnesses.

CHESTER E. ANDREWS.
